UNITED STATES PATENT OFFICE.

EARL B. HOUGH, OF STOCKTON, CALIFORNIA, ASSIGNOR TO IRVINE AND HOUGH COMPANY,
OF STOCKTON, CALIFORNIA, A CORPORATION.

ENDLESS-ROLL MECHANISM FOR PNEUMATIC MUSIC-PLAYERS.

No. 893,927.

Specification of Letters Patent.

Patented July 21, 1908.

Application filed November 6, 1907. Serial No. 400,913.

To all whom it may concern:

Be it known that I, EARL B. HOUGH, a citizen of the United States, residing at Stockton, in the county of San Joaquin and State of California, have invented certain new and useful Improvements in Endless-Roll Mechanism for Pneumatic Music-Players; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in music players and particularly to that class entitled pneumatic, my object being to produce such a roller mechanism as will be much simpler and cheaper of construction than the kind now used; also one which may be inserted and taken from the instrument with ease and despatch; also one which will be devoid of springs and similar complicated mechanisms; also one which will run true and smoothly and be kept close and tight over the tracker board, as is required. This object I accomplish by means of the general construction and relative arrangement of roller and guide mechanisms, and such other and further means as will appear fully by a perusal of the following specification and claims.

In the drawings similar characters of reference indicate corresponding parts in the several views.

Figure 1 is a side elevation of my complete mechanism. Fig. 2 is a sectional view thereof. Fig. 3 is a rear elevation of the roller mechanism. Fig. 4 is a perspective view of a roll carrying rack.

Referring more particularly to the characters of reference on the drawings 1 designates a box suitably pivoted at the lower inner corner as at 2 to an upright beam 3. Disposed on the side of said box 1 are pins 4 and 5 engaging hooks 6 and 7 on an arm 8 pivoted to the beam 3.

9 are plates secured to each side of the box 1 at the upper inner corners, said plates having upper bifurcated members 10 and lower bifurcated flanges 11.

Secured across the top of the box 1 and

journaled in the plates 9 is a shaft 12 on which is a roller 13 and a gear wheel 14 outside the said box, said wheel 14 intermeshing with a smaller gear 15 on a shaft 16, which shaft 16 is suitably journaled on the outside of one of the plates 9 and secured on which is a belt pulley 17 provided with a belt 18. 55

19 is a roller secured on a shaft 20 removably journaled in the members 10, which roller 19 bears normally against the roller 13. Also secured on the shaft 20 is a rack frame 21 having side members 22 having notches or depressions 23 formed therein, in the lower ends of which side members is secured a shaft 24 normally removably journaled in the bifurcations of the members 11. Secured on the shaft 24 intermediate 70 the members 22 is a roller 25. Disposed beneath the shaft 24 is a shaft 26 journaled in the flanged members 11 on which shaft is secured a roller 27.

28 designates the usual tracker board 75 which extends into and across from the notches 23.

29 designates the usual endless record sheet which passes between the rollers 13 and 19, over the roller 19, over the face of 80 the tracker board 28 and thence intermediate the rollers 25 and 27, the lower end of said sheet hanging loosely within the box 1.

In practice the usual power is applied to the belt 18 which drives the pulley 17, gear 15, gear 14 and roller 13, which action by reason of the roller 13 bearing tightly against the roller 19, advances the sheet 29 in the proper degree. The rollers 25 and 27 keep said sheet taut so that it fits tightly over the tracker board 28 as is necessary. The members 22 hold said sheet 29 in its proper transverse position, while the position of the rollers 13 and 19 prevents the sheet from turning under the same or crumpling. 95

When it is desired to remove the sheet 29 for any reason, the hooks 6 and 7 are unhooked from the pins 4 and 5 and the box 1 tilted forward until the hook 6 engages the pin 5, thus bringing the parts into easy reach. 100 The rack 21 and its parts are then dissociated for any desired purpose and when placed together the said rack is replaced in position again and the box 1 returned to normal position. 105

From the foregoing description it will be

seen that I have produced an endless roll mechanism which substantially fulfills all the objects of the invention as set forth herein.

While this specification sets forth in detail the present and preferred construction of the device, still such deviations from such detail may be resorted to as do not form a departure from the spirit of the invention.

Having thus described my invention what 10 I claim as new and desire to secure by Letters Patent is:—

1. In a device of the character described a box, bifurcated members at the upper end thereof, bifurcated lower flange members on 15 said box, a rack removably supported by said members, shafts in the upper and lower ends of said rack, rollers on said shafts, a roller disposed in said flange members just below the lower roller in said rack, and an 20 actuating roller disposed in said box and bearing against the upper roller on said rack, as set forth.

2. In a device of the character described, a rack, side members on said rack provided 25 with notches therein, a tracker board ex-

tending into and across said notches, and a roller mechanism in operative connection with said rack.

3. In a music player the combination of a box, means for swinging said box, an independent rack removably disposed in said box, and an endless roll mechanism disposed in said rack, as described.

4. In a music player, a box having upper and lower bifurcated members, a rack removably disposed in said bifurcated members, and a roller mechanism disposed in said rack, as set forth.

5. In a device of the character set forth a box, a removable rack therein, a roller disposed on said rack, an endless record sheet disposed over said roller, and an auxiliary roller disposed in said box and bearing against said sheet and roller, as set forth.

In testimony whereof I affix my signature 4 in presence of two witnesses.

EARL E. HOUGH.
